ELECTRIC SWITCH MECHANISM

Harold A. Duvall, Pasadena, and Charles G. Esler, Arcadia, Calif., assignors to Square D Company, Detroit, Mich., a corporation of Michigan

Application July 13, 1955, Serial No. 521,696

10 Claims. (Cl. 200—50)

This invention relates generally to switched fuse cabinets and more particularly to the operating, closing and switching mechanisms of a fused electrical switch.

One object of the invention is a dead front hinged cover switching device for a fuse panelboard.

Another object of the present invention is a novel overcenter operating mechanism for an enclosed fused switching device.

A further object of the present invention is an operating mechanism mounted on a hinged cover for an enclosed switching device adapted to be incorporated into a fuse panelboard in which the movable contacts of the switching device remain in the body of the device and the operating mechanism and external operator are movable with the hinged cover.

A further object of the present invention is a plug-in type distribution device including fuse holding means and switching means for opening and closing circuits through the device and in which the fuse holding means and the switching means are contained within the device enclosure and the operating mechanism and the external operator therefor are movable with relation thereto with a hinged cover for the enclosure.

A further object of the present invention is a switching device adapted to be incorporated into a fuse panelboard having movable bridging contacts and external operating mechanism in which the bridging contacts are rectilinearly movable within the device and the external operating mechanism is rotatable to effect the contact movement and in which an overcenter mechanism is provided intermediate the operator and the contacts for accomplishing the conversion of movements.

A further object of the present invention is the provision of an operating mechanism with a reversible external operator for an enclosed switching device adapted to be incorporated into a fuse panelboard whereby the device may be oriented in either of two directions and the external operator alone may be reversed with respect to the device so as to maintain a uniformity of appearance of several devices regardless of orientation when incorporated into a panelboard.

Other objects and features of the invention will be readily apparent to those skilled in the art from the following specification and appended drawings illustrating a certain preferred embodiment of the invention in which:

Figure 1 is a front elevational view of the switching device of the present invention shown in one of two alternative alignments.

Figure 2 is a sectional view taken along the lines II—II of Figure 1.

Figure 3 is a sectional view taken along the lines III—III of Figure 1.

Figure 4 is a sectional view taken along the lines IV—IV of Figure 3.

Figure 5 is an elevation and partial section view of the operating mechanism of the present invention taken along the lines V—V of Figure 3.

2

Figure 6 is a front elevational view of the switching device of the present invention with the device positioned in a second of two alternative positions and with the external operating mechanism shown in its reversed position.

Referring now to Figure 1 of the drawings illustrating the switching device of the present invention shown generally at 10 and comprising a folded sheet metal enclosure 12 and cover 14 hinged at 16 to an end plate 18 secured to the side enclosure 12 at one end thereof. The end plate 18 is provided with an extending flange 20 and a similar flange 22 is provided at the opposite end of the device to provide mounting areas for the positioning of the device in a distribution panelboard as shown in the copending application of Ralph H. Kingdon, S. N. 555,639, filed December 27, 1955, for Electrical Panelboard, and assigned to this same assignee. Generally centrally of the pivoted cover 14 is an external operator 24 rotatably supported on an escutcheon plate 26 and adapted to pass through the cover 14, as will be described hereinafter, to operate the operating mechanism of the switching device of the present invention. The escutcheon plate 26 is secured to the cover 14 by suitable screws 25 and, as will be described hereinafter, is reversible on the cover 14 to allow the device and the handle to be aligned in either of the two alternative positions. A conventional spring biased hook lock 27 is secured to the inside side wall of the enclosure 12, in a manner not herein illustrated, and passes through a slot 28 in the cover 14 to provide hooking and locking means for the cover in its closed position. The cover is also provided with a circular cutout hole 29 through which access may be had to a second cover locking mechanism, to be more fully described hereinafter, to permit opening movement of the cover 30 while the switching device is retained in its "on" position.

As illustrated in Figures 2, 3 and 4, the switching device of the present invention incorporates an assembly of a plurality of insulating blocks establishing spaced barriers and operating cutouts within which a suitable plurality of fuses and switching members may be supported and operated to accomplish switching and distribution of electrical energy through the device. The insulating base portions of the device constitute a contact base assembly 30, a contact cover assembly 32, and a fuse base assembly 34. The contact base assembly 30 is supported by suitable screws 36 and 37 which pass also, respectively, through the fuse base assembly 32 and the contact base cover assembly 34 to secure the insulating devices to a bottom plate 38 fixed by suitable screws 39 passing through the plate 38 and cooperating with a threaded bent over portion of bracket 40 suitably secured to the side plates 12 of the device as by means such as welding.

Referring now to Figure 2 wherein the contact base assembly 30 is shown as provided with a plurality of parallel recesses 42, 44 and 46, separated by insulating barriers 43 and 45, and establishing parallel operating channels for a like plurality of bridging contacts 47, 48 and 49 which are respectively secured to insulating blocks 51, 52 and 53 shown in Figure 4 by suitable screws such as 54. To the opposite ends of the insulating blocks 51, 52 and 53, a pair of operating hooks 55 are secured as by molding with the blocks 51, 52 and 53 so as to be permanently and securely fixed thereto. Each of the bridging contacts 47, 48 and 49 is provided with extending legs 56 and 57 which are individually adapted to cooperate with spring jaw clips 58 and 59 so as to electrically bridge the contacts and complete a circuit there-through as will be more completely described hereinafter.

An operating bail 60 extends through the cutout slots

62 in the hook shaped brackets 55 so as to jointly operate each of the insulating blocks 51, 52 and 53 with movement of the bail 60. The bail 60 is secured to the extending end 63 of a pair of operating levers 64 pivotally supported in each of the side plates 12 as by pivot studs 65 accommodated in suitable recesses 66 in the side plates 12 so that the flush surface of the side plates 12 may be maintained. The interior surface of the contact base assembly 30 is cut out at the edges at 67 and the central insulating barriers 43 and 45 are terminated generally centrally of the length of the contact base assembly to establish a generally arcuate operating area for the bail 60 and the side levers 64.

To the exterior of the switching device and to the outer base portion of the contact base assembly 30, a suitable plurality of spring jaw connectors 71 are secured with their associated bus connectors 72 of varying lengths so that the connectors 71 are disposed for the accommodation of isolated phases of a multiphase source and to one end of these conductors 72 folded over terminal straps 74 are secured as by studs 76. The folded over terminal straps 74 extend inwardly into the contact base assembly with a leg 78 at the extreme end of which are secured as by suitable rivets and conventional biasing members the spring jawed contacts 59.

Supported on the inside surface of the contact base assembly 30 is the previously mentioned contact base cover assembly 32 having an insulating base portion 80 and separating barriers 82. Between the insulating barriers 82 are supported a suitable plurality of spring fuse clips 84 on folded terminal conductors 85 secured to the base 80 of the contact base cover assembly by suitable screws at 86. Also secured to the terminal conductor 85 by screws 86 is an extending folded over terminal strap 87 passing through the base of the contact base cover assembly 32 and into the aligned recess in the contact base assembly 30 and at the extended end thereof there is secured thereto, as by suitable rivets and biasing springs the spring jaw clips 58, previously mentioned.

At the opposite end of the contact base assembly and to the interior surface thereof, the previously mentioned fuse base assembly 34 is secured as by the previously mentioned screw 36 and a similar screw 35 at the opposite end thereof. The fuse base assembly comprises an insulating base 90 and spacing insulation barriers 92 between which are supported a suitable plurality of spring fuse clips 94 on terminal straps 95 secured to the insulating base 90 by suitable screws 96. There may also be secured to the spring jaw fuse clips 94 and terminal strap 95 a suitable plurality of lugs 97 to which may be secured the conductors leading to the load devices to be controlled by the fused switching device of the present invention. It is to be understood that the end or the side walls of the enclosure will be provided with cutout or knockout openings through which the conductors to the load may pass.

To the inner surface of the hinged cover 14 of the switching device of the present invention the operating mechanism for the movable bridging contacts 47, 48 and 49, just described, is supported so that it may be pivotally moved with the cover to permit access to the interior mechanism of the device. The operating mechanism for the bridging contacts constitutes an external manual operator 24 and the internal overcenter snap-acting operating mechanism as shown in Figure 5 and generally designated 101. The external operator 24 is provided with a central shaft 102 extending through the escutcheon plate 26 and terminating inside of the hinged cover 14. To the interior end of the shaft 102, a cam arm 103 is secured by suitable screws 104 so as to be rotatable with the shaft 102 and at the free end of the cam arm 103 a cam collar 105 is supported on a cam pin 106 secured as by riveting to the interior surface of the cam arm 103 so as to extend inwardly toward the interior base assemblies. The operating mechanism is supported in a pan 107 having turned over edges 108 and the pan is secured

5 to a pair of channel members 109 secured as by welding to the interior surface of the cover 14, the pan 107 being secured as by screws 111 to the channels 109. Slidably supported within the pan 107 and between the pan and the cover 14 is a slide member 112 having a central cutout portion at 113 and folded over cam riders 114 at the edges of the cutout 113. The cam roller 105 on the cam member 103 moved by the operator 24 is positioned within the cutout 113 and is adapted to operate against the cam surface 114 to move the slide member 112 between the pan 107 and the cover 14 along the cutouts provided in the channel members 109. The slide member 112 is provided with an extension 115 having secured thereto by suitable means a bearing pin 116 about which a pair of spring guides 117 and 118 are positioned and held in place by means such as a cotter pin 119. Surrounding the spring guides 117 and 118 are a pair of springs 121 operating against shoulders of the spring guides near their pivoted ends and at the opposite ends against turned up shoulders 122 of a pair of pivoted toggle brackets 123 pivotally supported on the pan 107 by peened over rivets 124 so as to be rotatably supported for toggling action of the over-center spring mechanism. It should be readily apparent that as the cam roller 105 is arcuately moved 10 by the external operator 24 in contacting the cam surfaces 114 to reciprocate the slide member 112 between its two limits, as defined by the cutout channels in the channel members 109 at limits 110 at one end and at the other end a limit by rib 145, that the extending portion 20 115 will move through the overcenter position for the springs 121 so that, having passed through the overcenter position, the springs 121 will exert their biasing force to maintain the slide member 112 in an oppositely limited position against limits 110 from that indicated in 25 Figure 5.

An insulation barrier 124 is positioned between the operating mechanism 101 and the contact cover assembly 32 and the contact base cover assembly 34 and is supported by suitable rivets 125 on the inner surface of 30 the pan 107.

The reciprocating movement of the slide member 112 is transmitted to the operating lever 64 for the bridging contacts 47, 48 and 49 through the engagement of the operating end 130 of the lever 64 in cutout slots 131 45 of side extensions 132 of the slide member 112. As the slide member 112 is moved between its limits within the channel 109 and between the pan 107 and the cover 14, the operating lever 64 is reciprocated to transfer reciprocating motion to the bridging contacts 47, 48 and 49 through its engagement with the hook shaped brackets 55. This reciprocating motion is effected with a snap-action 50 due to the overcenter operation of the springs 121 to effect a both rapid and forceful movement of the bridging contacts into engagement with the spring contacts 58 and 55 59 so as to complete the circuit from the sources at spring clips 71 through the bridging contacts to the fuse clip 84 and thus through the fusing device, not herein shown, but normally positioned between the fuse clips 84 and 94 so as to provide at the lugs 97 the necessary energization 60 for a connected load device.

A lever lock mechanism is provided on one side of the enclosure 12 adjacent to the operating end 130 of lever 64 for insuring that the bridging contacts 47, 48 and 49 will not accidentally be moved to a position to bridge 65 the contacts 58 and 59 when the cover 14 is opened. For this purpose a locking lever 68 is pivotally supported on the side of the enclosure by a suitable rivet in the enclosure side as shown at 69. The locking lever 68 is spring biased by a resilient spring wire 70 operating at one end against the lip of the enclosure side and passes around the rivet 69 to operate, at its other end, against a notch in the lever so as to normally bias the locking lever 68 in a clockwise direction as viewed in Figure 3. The lever 70 is further provided with a bent over shoulder at 73 aligned for cooperation with an extending arm 100 on

inside surface of the pan 107 so that as the cover is closed, the arm will engage the shoulder 73 to rotate the locking lever 68 counter-clockwise about the rivet 69 and against the bias of the spring 70.

The end of the locking lever 68 opposite to the shoudered end 73 is adapted to engage a pressed out stop 75 on the operating lever 64 in its free unrestricted position. That is, when the cover 14 is opened, the locking lever 68 will rotate into aligned position with the stop 75 being limited in its clockwise rotation under the bias of spring 70 by the engagement of the end of the locking lever near the shoulder 73 with the lip of the enclosure 12. In this locking position, the lever 64 may not be rotated to slide the bridging contacts 47, 48 and 49 except by release of the locking lever 68. With the cover 14 closed, the locking lever 68 will be removed from locking alignment and the levers 64 may be operated in their normal fashion.

The operating mechanism for the fused switching device is further provided with a cover latching mechanism adjacent to the end of the operating mechanism which moves away from the sides of the enclosure 12 in opening movement of the cover 14. The latching mechanism constitutes a spring biased latch 135 pivotally supported on a rivet 136 on the pan 107 for rotatable movement. The latch 135 is formed into a substantially U shape with legs 137 and 138 disposed respectively adjacent to the cover 14 and the pan 107. Leg 138 of the latch 135, at its extremity, is formed into a latching surface 139, and is disposed for engagement with surface 141 of the end surface of the sides of the enclosure 12 so as to latch under the surface 141 and prevent opening movement of the cover 14. Opposite to the latching surface 139, on the leg 138, a spring guiding shoulder 142 is formed with a pressed out guide 143 so as to act both as a guide and a shoulder for a biasing spring 144 acting at one end against the shoulder 142 and at the opposite end against a stationary rib 145 of the pan 107. A portion of the rib 145 is bent over to form a guide 146 for that end for the biasing spring 144. Under unrestricted operation of the latch 135, the spring 144 will bias the latching surface 139 of the latch 135 into engaged position with the surface 141 of the enclosure for the switching device so that with the cover closed and with the latch 135 in engagement with the surface 141, the cover 14 may not normally be opened. To permit opening of the cover 14 while the latching surface 139 is in engageable position with the latching surface 141, a latch release means is accessible through an opening 29 in the cover 14. Coaxial with the rivet 136, the leg 137 of the latch 135 is provided with a screwdriver type accommodating slot 147 which may be engaged by a screwdriver blade or similar instrument passing through the cover 14. With this accommodation, the cover 14 may be opened even though the latch 135 is in normal engagement position with the latch surface 141 by inserting a screwdriver or similar instrument through the hole 29 to engage the slot 147 and then rotating the latch 135 to remove the latching surface 139 from its engagement with the latching surface 141.

Figure 5 illustrates the operating mechanism for the switching device of the present invention in its contacts open position, and illustrates the slide 112 in its limited position for this condition. The slide 112 is provided with an extending arm 151 which, in the position illustrated in Figure 5, extends through a folded over slot in the rib 145 at 152. The extending arm 151 is aligned to engage the bight portion of the latch 135 to rotate the latch in a counter-clockwise direction against the bias of spring 144 to remove the latch end 139 from its engaged position with the latching surface 141 of the end barrier of the side plates 12 of the enclosure, so that when the switch mechanism is in the open circuit or "off" condition, the cover 14 may be readily opened with release of the conventional latch 27 from engagement with the slot 28 as illustrated in Figure 1 of the drawings.

It should be apparent that with the cover in the open position, not herein illustrated, the external operator 24 may be manipulated to move the operating mechanism to either its "on" or "off" position; however, when the cover is returned to its enclosing position, the operating mechanism must be returned to the position of the internal switching mechanisms as established by the position of the extending arm 130 of the switch lever 64. If the operating mechanism is in a non-conforming position with extending arm 130 of the operating lever 64, the cover may not be closed due to the restricting non-alignment of the side extensions 132 of the slide 112 with the extending arm 130 of the operating lever 64.

Figure 6 illustrates the device of the present invention in a reversed mounting position with the escutcheon plate 26 in a reversed position with respect to the cover 14 of the device. The construction of the opening 113 in the slide member 112 and the construction of the operating cam roller 105 is such that the reversal of the escutcheon plate 26 with coincident reversal of operating lever 24 will return the operating cam roller 105 to its alignment within the slot 113 so that the operating mechanism can be maneuvered with movement of the external operator 24. This feature of the present invention is provided to accommodate the use of the switching device of the present invention within a load distributing fused panelboard wherein restricted areas are provided for the passage of connecting conductors from the lugs 97 of the switching device to the load devices they energize. Where a plurality of these switching devices are employed, adjacent or alternate switching devices may be reversed within the panelboard to permit distribution of the load conductors to either side of the panelboard thereby reducing both the congested condition of wiring gutters and permitting the employment of narrower gutters by the distribution of the load conductors. The reversal of the unit within the panelboard with coincident reversal of the escutcheon plate and operating handle maintains the systematic alignment of the escutcheon plates with merely the reversal of the operating handle from one side to the other of the cover. If alternate or adjacent units are reversed, the nameplate and load designations generally affixed to the escutcheon plate will be maintained in their proper alignment and the adjacent operating handles will merely have reversed alignment for their "off" and "on" conditions.

The operation of the switching device of the present invention is considered to be readily apparent from the description and operative analysis of the various components of the device hereinbefore presented. It should be understood that the device illustrated in the drawings is merely descriptive of one of many varieties dictated by both voltage and current ratings for the device illustrated and while only one preferred embodiment of the invention has been illustrated herein, it should be understood that further variations will be readily apparent to those skilled in the art and that the invention herein should not be limited to the specific disclosure shown but should be given its broadest possible interpretation within the terms of the following claims:

60. What is claimed is:

1. An electric switch comprising an enclosure, a hinged cover for said enclosure, insulating means supported within said enclosure, line contacts supported within said insulating means, load contacts supported within said insulating means, bridging contacts adapted to bridge said line and load contacts, said bridging contacts being supported within said enclosure for slidable movement within said insulating means, means within said enclosure for slidably moving said bridging contacts, and means supported on said cover for operating said means for moving said bridging contacts.

2. An electric switch comprising an enclosure, a hinged cover for said enclosure, insulating means supported within said enclosure, line contacts supported within said insulating means, load contacts supported within

said insulating means, bridging contacts adapted to bridge said line and load contacts, said bridging contacts being supported within said enclosure for slidable movement within said insulating means, lever means pivotally supported on said enclosure for slidably moving said bridging contacts, and snap acting operating means supported on said cover and engageable with said lever means for effecting movement of said lever means to move said bridging contacts.

3. An electric switch comprising an enclosure, a hinged cover for said enclosure, insulating means supported within said enclosure, line contacts supported within said insulating means, load contacts supported within said insulating means, bridging contacts adapted to bridge said line and load contacts, said bridging contacts being supported within said enclosure for slidable movement within said insulating means, lever means pivotally supported on the said enclosure for slidably moving said bridging contacts, means supported on said cover for effecting movement of said lever means including a member slidably movable contiguous to said cover, overcenter spring means biasing said member to either of two alternative positions and causing movement from one to the other of said positions to be with a rapid snap action, and means on said member engageable with said lever means for effecting movement of said lever means with a snap action to move said bridging contacts.

4. An electric switch comprising an enclosure, a hinged cover for said enclosure, insulating means supported within said enclosure, line contacts supported within said insulating means, load contacts supported within said insulating means, bridging contacts adapted to bridge said line and load contacts, said bridging contacts being supported within said enclosure for slidable movement within said insulating means, lever means pivotally supported on said enclosure for slidably moving said bridging contacts, operating means supported on said cover for said lever means including channel members fixed to said cover, a pan member fixed to said channel members, said pan member being spaced from said cover to provide an operating area therebetween, a slide member supported by said pan member and slideable between said pan and said cover in said operating area, overcenter spring means biasing said slide member to either of two alternative positions and causing movement from one to the other of said positions to be with a rapid snap action, means on said slide member engageable with said lever means for effecting movement of said lever means with a snap action to move said bridging contacts, and an external manual operator for manipulating said slide member.

5. An electric switch comprising an enclosure, a hinged cover for said enclosure, insulating means supported within said enclosure, line contacts supported within said insulating means, load contacts supported within said insulating means, bridging contacts adapted to bridge said line and load contacts, said bridging contacts being supported within said enclosure for slidable movement within said insulating means, lever means pivotally supported on said enclosure for slidably moving said bridging contacts, operating means supported on said cover for said lever means including channel members fixed to said cover, a pan member fixed to said channel members, said pan member being spaced from said cover to provide an operating area therebetween, a slide member supported by said pan member and slideable between said pan and said cover in said operating area, overcenter spring means biasing said slide member to either of two alternative positions and causing movement from one to the other of said positions to be with a rapid snap action, portions of said slide member being cut out generally centrally therof, folded edges of said central cut-out defining cam riders on said slide, an external operator, a cam roller fixed to said operator adjacent to the inner surface of said cover, said roller extending

into said central cut-out and being engageable with said cam riders to effect movement of said slide member with manipulation of said external operator, and means on said slide member engageable with said lever means for effecting movement of said lever means with a snap action to move said bridging contacts.

6. An electric switch comprising an enclosure, a hinged cover for said enclosure, insulating means supported within said enclosure, line contacts supported within said insulating means, load contacts supported within said insulating means, bridging contacts adapted to bridge said line and load contacts, said bridging contacts being supported within said enclosure for slidable movement within said insulating means, lever means pivotally supported on said enclosure for slidably moving said bridging contacts, operating means supported on said cover for said lever means including channel members fixed to said cover, a pan member fixed to said channel members, said pan member being spaced from said cover to provide an operating area therebetween, a slide member supported by said pan member and slideable between said pan and said cover in said operating area, an overcenter spring means biasing said slide member to either of two alternative positions and causing movement from one to the other of said positions to be with a rapid snap action, means on said slide member engageable with said lever means for effecting movement of said lever means with a snap action to move said bridging contacts, means for latching said cover to said enclosure and means operated by said slide member for releasing said latch means, and an external manual operator for manipulating said slide member.

7. An electric switch comprising an enclosure, a hinged cover for said enclosure, insulating means supported within said enclosure, line contacts supported within said insulating means, load contacts supported within said insulating means, bridging contacts adapted to bridge said line and load contacts, said bridging contacts being supported within said enclosure for slidable movement within said insulating means, lever means pivotally supported on said enclosure for slidably moving said bridging contacts, operating means supported on said cover, a pan member fixed to said channel members, said pan member being spaced from said cover to provide an operating area therebetween, a slide member supported by said pan member and slideable between said pan and said cover in said operating area, overcenter spring means biasing said slide member to either of two alternative positions and causing movement from one to the other of said positions to be with a rapid snap action, means on said slide member engageable with said lever means for effecting movement of said lever means with a snap action to move said bridging contacts, means for latching said lever means in contacts open position when said cover is open and means operated by said pan member for releasing said latch when said cover is closed, and an external manual operator for manipulating said slide member.

8. An electric switch comprising an enclosure, a hinged cover for said enclosure, insulating members supported within said enclosure, line and load contacts supported within said insulating members and bridging contacts supported within said insulating means and adapted to bridge said line and load contacts, an operating mechanism for manipulating said bridging contacts into engaged and disengaged position with said contacts, an external operator for said operating mechanism, said switch being adapted to be supported in either of two alternative orientations, and said external operator being reversible with respect to said switch to maintain a uniformity of alignment thereof regardless of the orientation of said switch.

9. An electric switch comprising an enclosure, a hinged cover for said enclosure, insulating members supported within said enclosure, line and load contacts supported within said insulating members and bridging contacts sup-

ported within said insulating means and adapted to bridge said line and load contacts, an operating mechanism for manipulating said bridging contacts into engaged and disengaged position with said contacts, an external operator for said operating mechanism, an escutcheon plate on the exterior surface of said cover for supporting said operator, said switch being adapted to be supported in either of two alternative orientations, and said escutcheon plate being reversible with respect to said switch on reversed orientation of said switch to maintain a uniformity of 10 alignment of said escutcheon plate and external operator regardless of orientation of said switch.

10. An electric switch comprising an enclosure, a hinged cover for said enclosure, insulating means supported within said enclosure, line contacts supported within 15 said insulating means, load contacts supported within said insulating means, bridging contacts adapted to bridge said line and load contacts, said bridging contacts being supported within said enclosure for slidable movement within said insulating means, lever means pivotally supported on 20 said enclosure for slidably moving said bridging contacts,

means supported on said cover for effecting movement of said lever means including a member slidably movable contiguous to said cover, portions of said member being cut out generally centrally thereof and defining a rectangular cam area, an external operator, a cam roller fixed to said operator adjacent to the inner surface of said cover, said roller extending into said rectangular cam area and being engageable therewith to effect movement of said slide member with manipulation of said external operator.
